GAS DISPENSING DEVICE

Le Roy L. Werner, Washington, D. C.

Application April 5, 1945, Serial No. 586,812

7 Claims. (Cl. 21—110)

(Granted under the act of March 3, 1883, as amended April 30, 1928; 370 O. G. 757)

1

The invention described herein, if patented may be manufactured and used by or for the Government for governmental purposes, without the payment to me of any royalty thereon.

This invention relates to a system of dispensing of gas stored in a container in liquefied form, more particularly to the dispensing of methyl bromide from a container in which it is stored in liquid form.

Methyl bromide is a gas having a boiling point of about 4.5° C. or about 40° F. This boiling point suits it for packaging in a container at a room temperature below its boiling point; it then is shipped safely and economically in the sealed container. When it is desired to use the methyl bromide, chiefly as a fumigant, the container is opened at a temperature above 4.5° C. and the gaseous methyl bromide is permitted to come in contact with the object to be treated. The standard can for shipping methyl bromide has a net content of one pound.

Difficulties in the application of methyl bromide and other gases stored in liquid form have been encountered due to the cooling effect which attends the vaporization of the liquid gas upon contact with atmosphere; this causes the temperature of the container to drop below the boiling point of the gas, and an equilibrium is thus reached and further vaporization stopped. Another problem peculiar to the handling of fumigating gases is the prevention of the escape of the poisonous gas into the atmosphere outside the fumigation system, particularly in the operation of opening the gas container.

The present invention provides a new, simple, safe, and economical system for the dispensing of methyl bromide or other liquefiable fumigant gases.

An object of the invention is the opening of a gas container in such a manner that the operator does not come in contact with the can during the opening operation.

Another object of the invention is the prevention of the escape of fumigating gas into the atmosphere outside the fumigating system.

Another object of the invention is the uninterrupted vaporization of the gas after the opening of the container in which it is stored in liquid form.

Yet another object is the utilization of the rest of the exhaust gases of a combustion engine associated with the fumigating apparatus for the utilization of the methyl bromide or other liquefied fumigant gas.

A further object of the invention is the opera-

tion of a fumigating system at an outside temperature below the boiling point of the fumigating gas, thereby making possible a fumigating operation in cool climates.

5 Still other objects of the invention will appear from the following description.

The accompanying drawings illustrate embodiments of the principle of the present invention.

10 Figure 1 is a front section view of a fumigating apparatus with a gas dispensing device in accordance with my invention.

15 Figure 2 is a lateral section through, and Figure 3 is a partly broken away front elevation of a modification of a gas dispensing system in accordance with my invention.

Figure 4 is a partly broken away front elevation of another of my system.

20 Figure 5 is a lateral section through another modification of my gas dispensing device.

I have discovered that the container of the liquid methyl bromide (or other substance with similar properties) may be safely opened by inserting the container into a compartment connected with the fumigating system by a conduit, and pressing the container by closing the lid of the compartment against the puncturing device which forms part of the fitting connecting the compartment and the fumigating system.

I have further discovered that the injurious cooling effect which attends the vaporization of the gas upon opening the container can be counteracted by heating the conduit or the compartment by means of exhaust gases from a combustion engine or other suitable sources of heat; in the use of a fumigating apparatus, I prefer to use the exhaust gases from the engine which drives the fan which is in the fumigating chamber.

25 In the following description of the drawings, 1 denotes a conventional fumigating chamber; 2 is a fan on the inside of the chamber for the circulation of the fumigating gas within the chamber. Fan 2 is driven by a small combustion engine 3 by means of a driving shaft 4 which passes through a wall of chamber 1 in a gas-tight packing box 5. A fumigating gas dispensing device 6, specially constructed in accordance with my invention (several embodiments of which will be described in detail below), is bracketed or otherwise attached to the outside of chamber 1, and a tube 7 for conducting the gas into chamber 1 leads from injector 6 to a point near fan 2 through a perforated rubber stopper 8 or other gas-tight packing

lodged in a wall of chamber 1. A pipe 9 leads from the exhaust of engine 3 through gas-dispensing device 6, and terminates in exhaust head or muffler 10.

In the following detailed description of an embodiment of a gas-dispensing device illustrated in Figures 2 and 3, which corresponds to device 6, shown in Figure 1, 11 denotes the can containing the methyl bromide or other similar substance as a liquid 12. The can is inserted into cylindrical compartment 13, the inner dimensions of which are slightly larger than the outer dimensions of can 11. Pivoted lid 14 of compartment 13 can be closed by means of a clamp comprising hook 15 and draw bolt 15' or other suitable pressure exerting means. In the bottom of compartment 13, preferably at its center, there is a perforation 16 through which passes the end of tube 7 which communicates with the fumigating chamber 1. The end of tube 7 is rigidly secured to the bottom of compartment 13 and terminates in a hollow point 17 having a perforation 18, the distance of point 17 from the upper level of compartment 13 being less than the height of can 11. The protruding end of tube 7 is surrounded by sleeve 19 of elastic and substantially gas-impermeable material, such as rubber, the bottom of the sleeve resting on the bottom of compartment 13. To open can 11 it is inserted into compartment 13 and lid 14 is closed by draw bolt 15. The bottom of can 11 is thus forced against point 17 and pierced; the contents 12 of can 11 then pass into tube 7 through perforation 18. Simultaneously, sleeve 19 is compressed and provides a gas-tight seal of the opening in can 11 against the outside.

Continuous vaporization of the contents 12 of can 11 is accomplished by surrounding compartment 13 with an annular housing or jacket 20 provided with inlet 21 and outlet 22 for the passage of exhaust or other hot gas, or hot liquid through housing 20, whereby heat is supplied to can 11; in the arrangement of Figure 1, inlet 21 is connected with exhaust pipe 9 leading from engine 3.

In the modification illustrated in Figure 4 the inner diameter of compartment 23 is somewhat larger than the diameter of can 11. Hot gases or hot water are passed through the hollow coil 24 (which in the arrangement of Figure 1 is integral with pipe 9) intermediate compartment 23 and can 11. A coiled electric resistance wire can be substituted for coil 24.

In the modification shown in Figure 5, a length of tube 7 is shaped into a coil 25 which is surrounded by jacket 26. Coil 25 in turn surrounds a length of pipe 27 which leads through jacket 26 for the passage of the hot fluid; in an arrangement according to Figure 5, pipe 27 is an integral portion of the exhaust gas pipe. Heat insulating material 28 may be placed between coil 25 and jacket 26 for confining in the heat exchange between pipe 27 and coil 25 to their immediate vicinity and for preventing dissipation of heat through jacket 26. Heat exchange between the hot fluid passing through pipe 27 and the fluid passing through coil 25 effects the desired vaporization of the latter fluid. The end of tube 7 beyond jacket 26 is integral with a can-piercing device 29 which pierces the can 11 and seals the punched hole against the atmosphere; can-piercing devices of this type are manufactured and sold commercially and I do not claim them as such. Can 11 is placed on top of jacket

26 and is clamped in place by conventional means. A jacket (not shown) may surround said can 11.

It is obvious that other modifications of the foregoing embodiments will readily occur to the expert. The scope of the invention is therefore not limited by these embodiments, which are in the nature of illustrations, but only by the appended claims.

I claim:

1. A fumigating system including a chamber; a fumigant-circulating fan in said chamber; a combustion engine for operating said fumigant-circulating fan; and fumigant-dispensing means comprising, in combination, heat exchange means at the outside of said chamber, said heat exchange means cooperating with a liquefied-fumigant-containing can, said fumigant having a boiling point below room temperature when unconfined, a fumigant-conduit leading from said heat exchange means into said chamber, an apertured hollow piercing point on that end of said conduit which is outside said chamber, said point being in can-piercing position, and lever means for urging said can against said point; said heat exchange means including fumigant-heating means comprising a pipe leading from the exhaust of said combustion engine and extending outside said chamber into heat-exchange relation with the liquefied fumigant without communicating with said fumigant, whereby said liquefied fumigant is vaporized prior to its entry into said chamber.

2. A fumigating system including a chamber; a fumigant-circulating fan in said chamber; a combustion engine for operating said fumigant-circulating fan; and fumigant-dispensing means comprising, in combination, a compartment at the outside of said chamber for receiving a liquefied-fumigant-containing can, said fumigant having a boiling point below room temperature when unconfined, a fumigant-conduit leading from said compartment into said chamber, an apertured hollow piercing point on that end of said conduit which is outside said chamber, said point being in can-piercing position, lever means for urging said can against said point, and fumigant-heating means comprising a pipe leading from the exhaust of said combustion engine and extending outside said chamber into heat-exchange relation with the side wall of said can in said compartment, whereby said liquefied fumigant is vaporized upon leaving said can.

3. A fumigating system including a chamber; a fumigant-circulating fan in said chamber; a combustion engine for operating said fumigant-circulating fan; and fumigant-dispensing means comprising, in combination, a compartment at the outside of said chamber for receiving a liquefied-fumigant-containing can, said fumigant having a boiling point below room temperature when unconfined, a fumigant-conduit leading from said compartment into said chamber, an apertured hollow piercing point on that end of said conduit which is outside said chamber, said point being in can-piercing position, lever means for urging said can against said point, and fumigant-heating means comprising a jacket surrounding said compartment and a pipe connecting the exhaust of said combustion engine with said jacket for conducting hot exhaust gas through said jacket into heat exchange relation with the side wall of said can in said compartment, whereby said liquefied fumigant is vaporized upon leaving said can.

4. A fumigating system including a chamber; a fumigant-circulating fan in said chamber; a combustion engine for operating said fumigant-circulating fan; and fumigant-dispensing means comprising, in combination, a compartment at the outside of said chamber for receiving a liquefied-fumigant-containing can, said fumigant having a boiling point below room temperature when unconfined, a fumigant-conduit leading from said compartment into said chamber, an apertured hollow piercing point on that end of said conduit which is outside said chamber, said point being in can-piercing position, lever means for urging said can against said point, and fumigant-heating means comprising a pipe leading from the exhaust of said combustion engine and terminating in a coil surrounding said can in said compartment for conducting hot exhaust gas into heat exchange relation with the side wall of said can in said compartment, whereby said liquefied fumigant is vaporized upon leaving said can.

5. A fumigating system including a chamber; a fumigant-circulating fan in said chamber; a combustion engine for operating said fumigant-circulating fan; and fumigant-dispensing means comprising, in combination, heat exchange means at the outside of said chamber, said heat exchange means cooperating with a liquefied-fumigant-containing can, said fumigant having a boiling point below room temperature when unconfined, a coiled fumigant-conduit leading from said heat exchange means into said chamber, an apertured hollow piercing point on that end of said conduit which is outside said chamber, said point being in can-piercing position, and lever means for urging said can against said point; said heat exchange means including fumigant-heating means comprising a pipe leading from the exhaust of said combustion engine and extending outside said chamber into heat exchange relation with said coiled fumigant-conduit without communicating with said fumigant, whereby said liquefied fumigant is vaporized in said coiled fumigant-conduit prior to its entry into said chamber.

6. A fumigating system including a chamber; a fumigant-circulating fan in said chamber; a combustion engine for operating said fumigant-circulating fan; and fumigant-dispensing means comprising, in combination, heat exchange means at the outside of said chamber, said heat exchange means cooperating with a liquefied-fumigant-containing can, said fumigant having a boiling point below room temperature when unconfined, a coiled fumigant-conduit leading from said heat exchange means into said chamber, and fumigant-heating means comprising a pipe lead-

ing from the exhaust of said combustion engine and extending outside said chamber into heat exchange relation with said coiled fumigant-conduit without communicating with said fumigant; said heat exchange means including a jacket surrounding said coiled fumigant-conduit and said pipe, and heat insulating means disposed in said jacket; whereby said liquefied fumigant is vaporized in said coiled fumigant-conduit prior to its entry into said chamber.

7. A fumigating system including a chamber; a fumigant-circulating fan in said chamber; a combustion engine for operating said fumigant-circulating fan; and fumigant-dispensing means comprising, in combination, heat exchange means at the outside of said chamber, said heat exchange means cooperating with a liquefied-fumigant-containing can, said fumigant having a boiling point below room temperature when unconfined, a coiled fumigant-conduit leading from said heat exchange means into said chamber, an apertured hollow piercing point on that end of said conduit which is outside said chamber, said point being in can-piercing position, and lever means for urging said can against said point; said heat exchange means including fumigant-heating means comprising a pipe leading from the exhaust of said combustion engine and extending outside said chamber into heat exchange relation with said coiled fumigant-conduit without communicating with said fumigant, a jacket surrounding said coiled fumigant-conduit and said pipe, and heat insulating means disposed in said jacket; whereby said liquefied fumigant is vaporized in said coiled fumigant-conduit prior to its entry into said chamber.
